UNITED STATES PATENT OFFICE.

JAMES RAMSEY SPEER, OF PITTSBURG, PENNSYLVANIA, ASSIGNOR TO
BROWNSVILLE GLASS COMPANY, OF PITTSBURG, PENNSYLVANIA, A
CORPORATION OF PENNSYLVANIA.

MANUFACTURING GLASS.

No. 818,247.

Specification of Letters Patent.

Patented Feb. 20, 1906.

Application filed April 1, 1905. Serial No. 263,257.

To all whom it may concern:

Be it known that I, JAMES RAMSEY SPEER, a citizen of the United States, residing at Pittsburgh, in the county of Allegheny and State of Pennsylvania, have invented or discovered new and useful Improvements in Manufacturing Glass, of which the following is a specification.

My invention relates generally to the manufacture of hollow glass articles, and more particularly to the manufacture of hollow glass cylinders produced as a step in the making of window-glass, though it is to be understood that I do not limit my invention to the production of any definite article which it is capable of making.

In the drawing of hollow cylinders by methods now in use they have a wavy appearance, due largely to waves of varying pressure propagated through the gaseous medium within the same. Cylinders made by said methods are fairly good for about the first five feet; but below this the cylinders are encircled by a series of transverse waves, which become more pronounced as the height of the cylinders increases. These waves are of course produced by the existence of an unbalanced or unequal pressure within the cylinders.

It is the object of my present invention to provide a remedy for the unequal pressures—in other words, to equalize the pressure within the cylinders whereby they may be drawn more perfectly than has hitherto been possible.

Other objects will appear in the description following.

In the drawings, which are merely illustrative of only a few forms which my invention may assume, Figure 1 shows the mechanism thereof partly in elevation and partly in vertical section, and Fig. 2 a similar view of a modification thereof.

Referring to Figs. 1 and 2 of the drawings, 45 1 designates vertical standards or masts on which the carriage 2 is mounted to slide vertically. The carriage is raised and lowered by means of the cable or other flexible device 3, which is secured at one end to the carriage 50 and at the other end to a winding-drum or other device. (Not shown.) The carriage 2 supports in any approved way the drawing-

tool 4 in such a manner that it can be readily detached therefrom.

5 represents a furnace supplied with heating devices, as the burners 6. The top of the furnace has the opening 7, through which the cylinders are drawn. In the opening 7 I mount the pot 8, which has the annular glass-holding cavity 9, the central boss 10 being provided with the opening 11. The bottom of the furnace 5 is provided with a guide-block 12, the upper end of the same being preferably in contact with the bottom of the pot in use.

Within the tube 12 is the air-inlet pipe 13, which extends through the opening 11 in the pot and slightly above the boss 10. The upper end of tube 13 is provided with the deflector 14, which directs the incoming air or other gas toward the junction of the cylinder and the molten glass, which junction I may designate the "drawing" zone.

15 is a main air-inlet pipe which is provided with one branch 16, leading to the tube 13, and a second branch 17, leading to the interior of the drawing-tool 4. An upwardly-opening cavity or other valve 18 is provided in the pipe 15, which valve will be opened, if for any reason the pressure in the pipe 15 rises above a definite limit, in order that the pressure transmitted to the interior of the cylinder shall not exceed the necessary amount.

If preferred, the pipes 16 and 17 may be connected to separate sources of pressure, as indicated in Fig. 2, in which the pipes 16 and 17 each has a valve 18.

19 is a bar normally supported by the cross-pin 20, which passes therethrough and rests on the top of the horizontal support 21. The latter has a slot through which the pin will pass to let the bar 19 down upon the valve.

The operation is as follows: The pot is placed as shown in Figs. 1 and 2. Molten glass is poured into the pot and the carriage 2 is lowered until the drawing-tool enters the glass slightly. After the glass adheres sufficiently to the tool the carriage 2 is elevated and air is admitted to the interior of the hollow cylinder, sufficient pressure being admitted to the cylinder to expand its contracted neck portion to the desired diameter for the cylinder. The pressure is regulated by the

bar 19 or in any other desired manner. The pressure within the cylinder should preferably remain substantially uniform during the subsequent drawing operation. If for any reason there should exist at one end of the cylinder a tendency to develop or transmit a change of density of the air within the cylinder, there would be a counteracting force at the opposite end through the branch tube leading thereto. The two tubes 16 and 17 tend to equalize the pressure within the cylinder and not only modify or nullify a change of density, but rather prevent the production of such a change. The valve or valves 18 also regulate the pressure of the air, as the air must pass the valve before reaching the cylinder. If the pressure should be excessive at the inlet 13, the valve will be opened and permit the excess to escape. After the cylinder has been formed it is severed from the bath in the pot and removed in any preferred manner.

I do not desire to be restricted to any of the details shown and described, as various means may be employed to equalize the pressure within the cylinders during their formation.

Having described my invention, I claim—

1. In an apparatus for drawing hollow glass bodies, wherein a gaseous pressure is supplied within the body during operation, means for equalizing the pressure throughout the body.
2. In an apparatus for drawing hollow glass bodies, means for containing the glass to be drawn, a drawing - tool arranged to draw a hollow body, means for supplying gaseous fluid to the interior of said body during the drawing operation, and means for equalizing the pressure of the gaseous fluid throughout the body.
3. In an apparatus for drawing hollow glass bodies, means for containing the glass to be drawn, a drawing - tool arranged to draw a hollow body, and a plurality of ducts

leading to different longitudinal portions of the interior of the glass cylinder being formed from means for supplying a gaseous fluid thereto.

4. In an apparatus for drawing hollow glass bodies, means for containing the glass to be drawn, a drawing - tool arranged to draw a hollow body, and a plurality of ducts leading separately from different longitudinal portions of the interior of the glass cylinder being formed to a common supply of gaseous fluid.

5. In an apparatus for drawing hollow glass bodies, means for containing the glass to be drawn, a drawing - tool arranged to draw a hollow body, a gaseous-fluid-supply pipe, and branch pipes connected thereto and leading from the exterior to different longitudinal portions of the interior of the cylinder being formed.

6. In an apparatus for drawing hollow glass bodies, means for containing the glass to be drawn, a drawing - tool arranged to draw a hollow body, a gaseous-fluid-supply pipe, and branch pipes connected thereto and leading to different longitudinal portions of the cylinder being formed.

7. A step in the process of drawing hollow glass bodies which consists in supplying gaseous fluid to the interior thereof simultaneously equalizing the pressure of the gas throughout the body.

8. A step in the process of drawing hollow glass bodies which consists in supplying gaseous fluid to the interior at two or more different points thereof simultaneously equalizing the pressure of the gas throughout the body.

Signed at Pittsburg, Pennsylvania, this 29th day of March, A. D. 1905.

J. RAMSEY SPEER.
